UNITED STATES PATENT OFFICE

PELLE ANDERSSON, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

CONDENSER

Application filed May 10, 1926. Serial No. 107,908.

This invention relates in general to improvements in the art of transferring heat, and relates more specifically to improvements in the construction and operation of surface condensers for steam.

An object of the invention is to provide a condenser which is simple in construction and efficient in operation. Another object of the invention is to provide improved instrumentalities for controlling the distribution of steam in a surface condenser. A further object of the invention is to provide improvements in hot-well construction and operation. These and other objects and advantages of the invention will be apparent from the following description.

A clear conception of embodiments of the several features of the present improvement and of the operation of devices constructed in accordance therewith, may be had by referring to the drawing accompanying and forming a part of this specification in which like reference characters designate the same or similar parts in the several views.

Fig. 1 is a part sectional and somewhat diagrammatic end view of an improved surface condenser.

Fig. 2 is a fragmentary enlarged section taken transversely through the surface condenser and showing the flow control mechanism in one position of adjustment.

Fig. 3 is an enlarged fragmentary sectional view taken transversely through the condenser and showing the flow control means in another position of adjustment.

Fig. 4 is an enlarged central vertical section through one form of improved hot-well construction.

Fig. 5 is an enlarged central vertical section through another form of improved hot-well construction.

The improved surface condenser specifically illustrated in the drawing, comprises in general a main casing 2 which may be of elliptical cross section and which provides a housing for a plurality of parallel tubes; a conduit 4 providing steam admission means communicating with the upper side or top of the casing 2; a hot-well providing condensate discharge means communicating with

the lower side or bottom of the casing 2; and the usual means, not shown, for admitting cooling water to the interior of the tubes 3.

The tubes 3 located within the casing 2 are arranged in four nests or groups, these groups being separated to provide a vertical enlarged lane 12 extending centrally through the casing from the inlet 4 to the hot-well 5, and to provide horizontal enlarged spaces or lanes 13, 14 extending laterally from the central lane 12 to the opposite sides of the casing 2. The upper portion of the central lane 12 is preferably made downwardly converging as shown, and it should be understood that steam admitted to the lanes 12, 13, 14 is capable of freely entering the spaces between the tubes directly adjacent to these lanes.

Located directly adjacent to the junction between the lanes 12, 13, 14, is a set of flow control plates 7, 8 shown in detail in Figs. 2 and 3. These plates extend throughout the length of the condensing chamber and are mounted for pivotal movement about parallel rods 26 supported in any convenient manner. The plate 7 is rigidly attached to a pair of end levers 15 the swinging ends of which carry pins 17. The plate 8 is rigidly attached to a pair of similar end levers 16 having elongated slots engaging the pins 17 of the levers 15. The pivots 26 are supported by one or more brackets which are rigidly attached to a support 11 located centrally within the casing 2. An actuating rod 9 is pivotally attached to the rear of the plate 8 and extends through the lane 14, the end of this rod being screw threaded and coacting with the screw threaded interior of an adjusting element 10 comprising a hand wheel and an externally threaded member coacting with a screw threaded plate secured to the casing 2.

The hot-well 5 shown in Fig. 4, comprises an outer cup shaped casing the upper end of which communicates directly with the condensate collecting space 27 at the lower end of the main condenser casing 2. As illustrated, the hot-well 5 besides being made very large in diameter, has considerable depth. The condensate discharge pump 6 has its suction 23 communicating directly with the in-

terior of a central cup 20. Located within the outer casing of the hot-well and surrounding the cup 20 therein, is a cylindrical wall 18 which extends upwardly above the outer wall of the hot-well 5 and provides an annular space 22. The space 22 surrounding the wall 18 communicates with the space within this wall through a series of openings 24 penetrating the lower end of the wall 18. Located within the wall 18 and surrounding the cup 20 is a steam or other hot fluid admission coil 19 the upper end of which communicates with the space within the wall 18 and the lower end of which communicates with a steam admission pipe 21.

The hot-well 25 shown in Fig. 5, comprises an outer cup shaped casing the upper end of which communicates directly with the condenser collecting space 27 at the lower end of the main condenser casing 2. As illustrated, the hot-well 25 while being of relatively large diameter, is not as deep as the hot-well 5 illustrated in Fig. 4. The condensate discharge pump 6 of the embodiment shown in Fig. 5, has its suction 33 communicating directly with the interior of a central cup 30 which extends downwardly below the main hot-well casing. Located within the main outer casing of the hot-well 25 and surrounding the upper extremity of the cup 30 therein, is a cylindrical wall 28 which extends upwardly above the end of the outer wall of the hot-well 25, and provides an annular space 32. The space 32 surrounding the wall 28 communicates with the space within this wall through a series of openings 34 penetrating the lower end of the wall 28. Within the wall 28 is also located a hot fluid admission coil 29 surrounding the upper extremity of the cup 30. The upper end of the coil 29 communicates with the space within the wall 28 and the lower end of the coil communicates with a steam admission pipe 31.

During normal operation of the condenser, the steam is admitted to the top of the casing 2 through the inlet 4 and cooling fluid is passed through the tubes 3. As the steam passes through the spaces between the relatively cool tubes 3, it is ultimately condensed and the water of condensation flows downwardly through the condensate collecting space 27 to the hot-well 5 or 25 communicating with this space. If the control plates 7, 8 are disposed as shown in Figs. 1 and 2, a considerable volume of the steam is free to flow downwardly through the central lane 12 and laterally directly to the lower tubes of the condenser. If however the plates 7, 8 are adjusted to the position indicated in Fig. 3, the steam which enters the converging upper portion of the lane 5 is caused to flow laterally through the lanes 13, 14, upon striking inclined plates 7, 8. The steam thus admitted to the lanes 13, 14 is free to flow downwardly directly through the spaces of the lower

groups of tubes thus insuring effective utilization of the tubes of these groups. The steam entering through the inlet 4 assures effective utilization of the tubes of the upper groups, thus insuring best efficiency of operation of all of the tubes within the casing 2. It will be apparent that the plates 7, 8 may also be set in an intermediate position whereby partial divergence of the flow through the central lane 12 to the lanes 13, 14, may be effected, and the plates 7, 8 may be readily adjusted during normal operation of the condenser by manipulating the element 10.

The hot-well is formed of relatively large diameter and of great depth, and the connection from the pump 6 to the hot-well is such, that at no load or at light loads when the water in the hot-well is low, the pump suction will be submerged thus preventing air from entering the pump 6. By virtue of the double wall construction of the hot-well, the condensate is brought into contact with the hot fluid admission pipe 19 or 29 and is caused to boil thereby driving off the air prior to delivery of the condensate to the pump 6. The admission of hot fluid to the hot-well through the pipe 19 or 29 cooperates with the distributing plates 7, 8, to reduce the temperature drop through the condenser to a minimum, thereby avoiding so called "refrigeration", and producing final discharge liquid of desirably high temperature.

It should be understood that it is not desired to limit the invention to the exact details of construction and operation herein shown and described, for various modifications within the scope of the claims may occur to persons skilled in the art.

It is claimed and desired to secure by Letters Patent:

1. In combination, a casing, a plurality of tubes within said casing, steam admission means communicating with one side of said casing, condensate discharge means communicating with the opposite side of said casing, said tubes being grouped to provide a central lane affording means of direct communication between said admission means and the space surrounding the tubes adjacent to said discharge means, and means for controlling the flow of fluid through said lane.

2. In combination, a casing, a plurality of tubes within said casing, steam admission means communicating with the top of said casing, condensate discharge means communicating with the bottom of said casing, said tubes being grouped to provide a lane extending downwardly between groups of said tubes and affording means of direct communication between said admission means and the space surrounding the tubes adjacent to said discharge means, and pivotally supported plates for controlling the flow of fluid through said lane.

3. In combination, a casing, a plurality of

tubes within said casing, steam admission means communicating with the top of said casing, a hot-well communicating with the bottom of said casing, said tubes being grouped to provide a central lane directly connecting said admission means with the space surrounding the tubes near said hot-well and to provide other lanes extending transversely of said central lane, and means for controlling the flow of fluid through said lanes.

4. In combination, a casing, a plurality of tubes within said casing, steam admission means communicating with the top of said casing, condensate discharge means communicating with the bottom of said casing, said tubes being grouped to provide a central lane directly connecting said admission means with the space surrounding the tubes near said hot-well and other lanes extending laterally of said first mentioned lane, and means for alternately conducting fluid directly through said central lane to the tubes near said hot-well or through a portion of said central lane and laterally thereof between said groups of tubes.

5. In combination, a casing, a plurality of tubes within said casing, means for admitting steam to said casing, a hot-well communicating with said casing, said hot-well comprising inner and outer walls forming an annular condensate receiving space, and a pump communicating with the interior of said inner wall.

35 6. In combination, a casing, a plurality of tubes within said casing, means for admitting steam to said casing, a hot-well comprising central and annular spaces in open communication with the interior of said casing, means for admitting heating fluid direct to said hot-well, and a pump communicating with the space within the inner bounding wall of said annular spaces.

7. In combination, a casing, means for admitting steam to said casing, a hot-well having an annual chamber communicating with said casing, a heating coil within the inner bounding wall of said chamber, and a pump communicating with the space within said inner wall.

55 8. In combination, a casing, means for admitting steam to said casing, a hot-well having an annual chamber formed to receive condensate at one end from said casing, and to deliver said condensate at the opposite end into the space within the inner bounding wall of said chamber, means for heating the condensate delivered from said chamber, and a pump for removing the condensate after heating.

60 9. In combination, a casing, a plurality of tubes within said casing, steam admission means communicating with one portion of said casing, a hot-well communicating with another portion of said casing, said tubes be-

ing grouped to provide intersecting vertical and horizontal distributing lanes therebetween, adjustable means located at the intersection of said lanes for controlling the flow of fluid through said lanes, and means for heating the condensate delivered to said hot-well.

75 10. In combination, a casing, a plurality of groups of tubes within said casing separated by intersecting lanes, steam admission means communicating with one end of one of said lanes, a hot-well having an annular chamber communicating with the opposite end of said lane, means located at the intersection of said lanes for controlling the distribution of steam between said groups of tubes, means for heating the condensate delivered to said hot-well, and a pump for removing the heated condensate from said hot-well.

80 11. In combination, a casing, a plurality of groups of tubes within said casing separated by intersecting lanes, and adjustable means located at the intersection of said lanes for controlling the flow of fluid admitted to said casing between said groups of tubes.

85 12. In combination, a casing, a plurality of groups of tubes within said casing separated by a vertical lane and other lanes extending laterally from said vertical lane, and adjustable means located at a point of communication between several of said lanes for controlling the distribution of fluid entering said casing between said groups of tubes.

90 13. A surface condenser comprising a shell having a steam inlet and outlet for condensate and uncondensable gases, a plurality of cooling tubes arranged transversely to the steam flow, means for by-passing steam about a number of the tubes and additional means for directing the by-pass steam onto others of the tubes.

100 14. A surface condenser comprising a shell having a steam inlet and outlet for condensate and uncondensable gases, a plurality of groups of cooling tubes arranged transversely to the path of steam flow, means to by-pass steam about certain groups of tubes, and separate means for directing the by-passed steam directly onto another group of tubes.

CERTIFICATE OF CORRECTION.

Patent No. 1,792,796.

Granted February 17, 1931, to

PELLE ANDERSSON.

It is hereby certified that error appears in the printed specification of the above numbered patent requiring correction as follows: Page 3, lines 40 and 41, claim 6, for the words "said hot-well" read the space within the inner bounding wall of said annular space; same page and claim, line 43, for "spaces" read space; and that the said Letters Patent should be read with these corrections therein that the same may conform to the record of the case in the Patent Office.

Signed and sealed this 14th day of April, A. D. 1931.
